CLAIM

The ornamental design for an athletic basketball training tool, substantially as shown and described.

DESCRIPTION

FIG. 1 is a front perspective view of an athletic basketball training tool showing my new design.

FIG. 2 is a front elevation view thereof.

FIG. 3 is a rear elevation view thereof.

FIG. 4 is a right side view thereof.

FIG. 5 is a left side view thereof.

FIG. 6 is a top view thereof; and,

FIG. 7 is a bottom view thereof.

The broken lines are for the purpose of illustrating the portions of the athletic basketball training tool that form no part of the claimed design.
